UNITED STATES PATENT OFFICE.

GEORGE WESTINGHOUSE, OF PITTSBURG, PENNSYLVANIA.

GEARING.

No. 922,827.

Specification of Letters Patent. Patented May 25, 1909.

Application filed April 29, 1897, Serial No. 634,467. Renewed November 16, 1908. Serial No. 462,914.

To all whom it may concern:

Be it known that I, GEORGE WESTINGHOUSE, a citizen of the United States, residing at Pittsburgh, in the county of Allegheny and State of Pennsylvania, have invented or discovered a certain new and useful Improvement in Gearing, of which improvement the following is a specification.

The object of my invention is to provide improved means for transmitting motion from one rotating part or member of a machine or mechanism to another; and to this end my invention consists of a novel construction and combination of friction gearing for effecting such transmission of motion.

In the accompanying drawings: Figure 1 is a central longitudinal section illustrating an application of my improvement; Fig. 2, a view showing the driving shaft and friction device of Fig. 1, on a larger scale; Fig. 3, a section through the casing and shaft at the right of the friction wheels as shown in Fig. 1, on a slightly larger scale than Fig. 1; Figs. 4 and 5, detail views, on a larger scale, showing a modification of the construction shown in Figs. 1 and 2, and Fig. 6, a detail view of a modification on the same scale as Figs. 3 and 4.

Within the casing, 1, is fitted a tapered ring, 2, which is cut or split diagonally so that it may be adjusted by being forced into the tapered bore of the casing. Through the head 3, of the casing, extends a shaft 4, carrying a disk 5, in which pins 6, 7, and 8 are tightly fitted, at equal distances apart, and at equal distances from the center of the disk. Friction wheels 9, 10, and 11, are mounted to rotate on the pins 6, 7, and 8, and engage with and roll on the ring 2. A central shaft, 12, extends into the casing, with its axis in line with the axis of the shaft 4, in position to engage with each of the wheels 9, 10, and 11. When the shaft 12 is rotated, it imparts rotary motion to the wheels 9, 10, and 11, on the pins 6, 7, and 8, and the engagement of the wheels 9, 10, and 11, with the ring 2, causes them to roll on the ring, and thus rotate the disk 5 and the shaft 4. This general construction of gearing is substantially similar to one of the forms shown and described in my pending application, Serial No. 501,140, filed February 23, 1894, and I do not, therefore, claim it herein otherwise than as combined with the improved friction device herein described.

In the above recited pending application

the end of a driving shaft forms the central pinion or driving wheel by which the planet wheels of the friction gearing are rotated. In my present improvement, the portions 13 and 14, of the driving shaft, 12, which engage the wheels, 9, 10, and 11, are of the proper diameter to secure the desired velocity ratio between the shaft and the wheels, and, in the drawings, they are shown as having the same diameter as the shaft, but they may have a greater or less diameter than the shaft, and may be formed either integral with the shaft or as a separate part, or parts, and secured to the shaft in any suitable manner.

Between the portions 13 and 14, the shaft is reduced in diameter and wound with one or more coils of wire, 16, 16^a; the thickness of the wire being such that the outside diameter of the coils when wound on the shaft will be substantially equal to the diameter of the portions 13 and 14 and will therefore engage with the rims of the wheels 9, 10, and 11. Each coil of wire is fixed at one end and free at the other end; the fixed end 18 being tightly fitted in a hole 19 drilled in the shaft.

When the shaft 12 is rotated in the same direction that the coil is wound from the fixed end, the friction between the coil and the rims of the wheels tends to uncoil the wire and enlarge or expand the diameter of the coil, thereby pressing the wire out away from the shaft and against the rims of the wheels and increasing the friction and the driving power which may be transmitted from the shaft to the wheels.

The construction illustrated in Figs. 1 and 2, which has but a single coil of wire, may be employed when the rotation of the shaft 12 is always in the same direction, and it is not desired that it should be reversed.

In Figs. 4, and 6, I have shown two coils of wire, wound in the same direction on the shaft, and having their adjacent ends secured to the shaft. With this construction the shaft may be rotated in either direction, the additional friction and gripping effect being secured by the coil 16 when the shaft is rotated in one direction and by the coil 16^a when the shaft is rotated in the opposite direction. When both coils of wire are wound in the same direction on the shaft, as shown in Figs. 4 and 6, either the adjacent or the opposite ends of the wire may be fixed. If the two coils of wire are wound in

opposite directions, their alternate ends shall be fixed. As shown in Fig. 6, the wire, instead of being round, may be square or rectangular in cross section, so that the coils 5 will lie close together and form a more regular external surface.

My invention is not limited to the specific construction shown, as the form of the metallic coil or wrapping may be further varied, 10 and, if preferred, a number of super-imposed coils may be employed, or a wrapping or winding of metal having a different cross sectional form may be employed; for instance, a sheet or layer of metal may be 15 secured at one edge and wrapped about the shaft or pulley so that its other edge abuts against or overlaps the fixed edge.

A pulley or shaft provided with my improvement may be employed in connection 20 with one or more friction pulleys, and its application is, therefore, not limited to the particular arrangement of wheels shown in the drawing.

The characteristic features of the coil, 25 winding, or wrapping employed in the present case, are these: that the material of which it is composed shall be elastic and resilient, and sufficiently rigid to preserve a substantially circular or cylindrical shape, even though attached to the shaft at but one point in any one convolution. These features being present, the best results will be secured if a slight degree of play, or the capacity of a slight radial movement, be provided in the application of the coil, winding, or 35 wrapping, elsewhere than at a point, or points, of attachment, whereby it may have a slight degree of expansibility or compressibility, that is, radially from and toward the shaft. Further, the best results will ordinarily be 40 secured if the convolutions be sufficient in number, that is, counting from the point of attachment, to provide for a slight circumferential motion of the coil, winding, or wrapping, in the direction of its length, 45 as it may become expanded or be compressed.

I claim as my invention and desire to secure by Letters Patent:

50 1. The combination with a shaft, wheel, or pulley, of two metallic coils or wrappings each fixed at one end to the shaft, wheel, or pulley and wound in such a direction relatively to its fixed end that either coil may 55 operate under the action of the tangential force as a friction device according to the direction in which the shaft is rotated, substantially as set forth.

2. In a mechanism for transmitting motion, a rotatable member, two resilient friction agents fixed at one end to said member and so arranged that either agent may operate under the agency of a tangential force to 60 transmit power according to the direction in 65 which the shaft is rotated.

3. In a mechanism for transmitting motion, a stationary casing, a driving shaft and a driven shaft extending into said casing, a plurality of planetary gears mounted on said driven shaft, a resilient friction agent mounted on said driving shaft and adapted to drive said planetary gears during the rotation in one direction of said driving shaft and to automatically disconnect when said shaft is driven in the opposite direction. 70

4. In a mechanism for transmitting motion, a driving member, a driven member, a plurality of planetary gears mounted on said driven member, a casing inclosing said gears and adapted to coöperate therewith, a resilient friction agent mounted on said driving member and adapted to drive said planetary gears during the rotation in one direction of said driving member and to automatically disconnect when said driving member is 80 driven in the opposite direction. 75

5. In a mechanism for transmitting motion, a driving member, a driven member, a plurality of planetary gears mounted on said driven member, a stationary casing inclosing 90 said gears adapted to coöperate therewith, a resilient friction agent mounted on said driving member and adapted to drive said planetary gears during the rotation in one direction of said driving member and to automatically 95 release said gears when said shaft is driven in the opposite direction.

6. In a mechanism for transmitting motion, a driving member, a driven member, a resilient friction agent mounted on said driving member, a speed-changing device between said resilient member and said driven member adapted to coöperate therewith and to transmit motion to said driven member through said speed changing device when the driving member is rotated in one direction and to automatically break the driving connection when said driving member is driven in the opposite direction. 100

7. In a mechanism for transmitting motion, a driving member, a driven member, a speed-changing device and a resilient friction agent between said members adapted to drive said driven member during the rotation in one direction of said driving member and to automatically break the driving connection when said driving member is driven in the opposite direction. 110

8. In a mechanism for transmitting motion, a driving member, a driven member, a speed-changing device and a resilient friction agent between said members adapted to drive said driven member during the rotation in one direction of said driving member and to break the driving connection when said driving member is driven in the opposite direction. 120

9. In a mechanism for transmitting motion, an inclosing casing, a driving shaft extending into said casing, a driven shaft, a 130

plurality of gears mounted on said driven shaft and a resilient friction agent mounted on said driving shaft and adapted to drive said gears during the rotation in one direction 5 of said driving shaft and to automatically disconnect when said shaft is driven in the opposite direction.

10. In a mechanism for transmitting motion, an inclosing casing, a driving shaft extending into said casing, a driven shaft, a plurality of gears mounted upon said driven

shaft, and two resilient friction agents fixed at one end of said driving shaft and so arranged that one of said agents will drive said gears regardless of the direction of rotation of 15 said driving shaft.

In testimony whereof, I have hereunto set my hand.

GEO. WESTINGHOUSE.
